UNITED STATES PATENT OFFICE.

VICTOR YORK AND WALTER G. BLACK, OF BREA, CALIFORNIA.

OIL-WELL DRIVE.

1,277,166.

Specification of Letters Patent. Patented Aug. 27, 1918.

Application filed July 9, 1917. Serial No. 179,553.

To all whom it may concern:

Be it known that we, VICTOR YORK and WALTER G. BLACK, both citizens of the United States, residing at Brea, in the 5 county of Orange and State of California, have invented a new and useful Oil-Well Drive, of which the following is a specification.

Our invention relates to the art of drilling 10 oil wells by the so-called rotary system. In that system it is common practice to rotate a string of drill pipes which carry the cutting bit at their lower end. This drill pipe is ordinarily rotated by a rotary table which 15 is driven through suitable chain gearing from a gas engine. In the ordinary form of table drive a sprocket is placed directly adjacent to the table, and a driving chain is run across the derrick floor from suitable 20 mechanism located at the side of the derrick. These chains form a serious life hazard, frequently breaking and whipping about in the derrick, thereby endangering the lives of the men working on the derrick floor.

25 The principal object of our invention is to provide a drive which will have all the flexibility and resiliency of the present chain drive without its dangers.

Referring to the drawings, which are for 30 illustrative purposes only:

Figure 1 is a plan view of a derrick equipped with our invention.

Fig. 2 is a side elevation of the apparatus attached to the derrick, as viewed in the 35 direction of the arrow 4 of Fig. 1.

Fig. 3 is a side elevation of the apparatus shown in Fig. 1.

In the form of our invention illustrated 40 in these drawings, a rotary table 11 is shown, this table being suitably secured to the derrick floor 12 and engaging the drill pipe 13 or a drill stem secured thereto. The table 11 is provided with beveled teeth 14 which are engaged by a bevel pinion 15 secured to 45 a stud shaft 16 turning freely in bearings 70. The stub shaft 16 is engaged by a coupling 18 on a jack shaft 19 which is carried in a bearing 20 near the table 11, and in a bearing 21 at the edge of the derrick floor.

50 Mounted on the extreme end of the jack shaft 19 is a bevel gear 22 which is engaged by a bevel pinion 23 carried on a secondary shaft 24. The secondary shaft 24 is

mounted in bearings 25. In addition to the bevel gear 23, which is rigidly secured to 55 the shaft 24, a sprocket 26 is also rigidly secured to this shaft, carrying a chain 27 which passes over a sprocket 28 rigidly secured on a primary shaft 29. The primary shaft 29 is driven by means of a sprocket 30 60 and a chain 31 from a prime mover 32, in accordance with standard practice. The shaft 29 also drives a shaft 35 which carries certain apparatus needed in the drilling of the well. 65

The method of operation of the invention will be obvious, the engine 32 driving the shaft 29 through the chain 31, and in turn driving the shaft 24 through the chain 27. The shaft 24 drives the shaft 19 through the 70 gears 22 and 23, and the shaft 19 drives the shaft 16 through the coupling 18. Shaft 16 drives the table 11 through the bevel pinion 15 and the gear teeth 14. The table in turn drives the drill pipe 13. 75

It will be noted that two chains 31 and 27 are interposed between the prime mover 32 and the drilling string 13. It will further be noted that these chains are both off the drilling floor, so that advantage can 80 be taken of their resiliency without endangering the lives of the men working around the table 11.

We claim as our invention:—

1. An oil well drive for use in a derrick 85 comprising a rotary table, a bevel gear formed thereon; a bevel pinion driving said bevel gear; a jack shaft on which said pinion is secured, said jack shaft extending across the floor of and outside said derrick; 90 a secondary shaft located at right angles to said jack shaft outside said derrick; bevel gears connecting said jack shaft to said secondary shaft; a primary shaft located above and parallel to said secondary shaft; a chain 95 and sprockets connecting said primary and secondary shafts; a prime mover; and a chain and sprockets connecting the shaft of said prime mover with said primary shaft.

2. An oil well drive for use in a derrick 100 comprising a rotary table, a bevel gear formed thereon; a bevel pinion driving said bevel gear; a stub shaft on which said bevel pinion is secured; a jack shaft connected to said stub shaft, said jack shaft extending across 105 the floor of and outside said derrick; a sec-

ondary shaft located at right angles to said jack shaft outside said derrick; bevel gears connecting said jack shaft to said secondary shaft; a primary shaft located above and parallel to said secondary shaft; a chain and sprockets connecting said primary and secondary shafts; a prime mover; and a chain

and sprockets connecting the shaft of said prime mover with said primary shaft.

In testimony whereof, we have hereunto set our hands at Brea, California, this 29th day of June, 1917.

VICTOR YORK.
WALTER G. BLACK.
